UNITED STATES PATENT OFFICE

110,152

DESIGN FOR AN ELECTRIC FENCE CONTROL CASING

Sidney A. Moore, Milwaukee, Wis., assignor to
The Prime Manufacturing Company, Milwaukee, Wis., a corporation of Wisconsin

Application April 4, 1938, Serial No. 76,276

Term of patent 7 years

To all whom it may concern:

Be it known that I, Sidney A. Moore, a citizen of the United States, residing at Milwaukee, in the county of Milwaukee and State of Wisconsin, have invented a new, original, and ornamental Design for an Electric Fence Control Casing, of which the following is a specification, reference being had to the accompanying drawing, forming part thereof.

Figure 1 is a perspective view taken from one

end and the front of the electric fence control casing; and

Figure 2 is a perspective view taken from the rear and the opposite end of the electric fence control casing.

I claim:

The ornamental design for an electric fence control casing, as shown.

SIDNEY A. MOORE.
